(57) **ABSTRACT**

A multi-band antenna array includes a plurality of first antennas for resonating at a first band, and a plurality of second antennas for resonating at a second band. A frequency of the second band is higher than a frequency of the first band. Locations of the plurality of first antennas project to a plurality of grid-one positions on a surface; locations of the plurality of second antennas project to a plurality of grid-two positions on the surface. Among the grid-one positions, a second grid-one position is nearest to a first grid-one position by a first distance along a first direction. Among the grid-two positions, a first grid-two position and a second grid-two position are closest two to the first grid-one position. The first and second grid-two positions are separated by a second distance along a second direction; and, the first direction and the second direction are nonparallel.

MULTI-BAND ANTENNA ARRAY

This application claims the benefit of U.S. Provisional application Ser. No. 62/558,376, filed Sep. 14, 2017, the subject matter of which is incorporated herein by reference.

FIELD OF THE INVENTION

The present invention relates to a multi-band antenna array, and more particularly, to a multi-band antenna array with antennas of different bands arranged adjacently along different directions for improving compactness.

BACKGROUND OF THE INVENTION

Antenna module is essential for devices which require wireless functionality, such as mobile phones which require mobile telecommunication. Modern advanced wireless functionality, such as 5G (fifth generation) mobile telecommunication, demands multi-band antenna module capable of signaling (transmitting and/or receiving) at multiple RF bands of different frequencies. In addition, limited form factor of wireless device constrains size of antenna module.

SUMMARY OF THE INVENTION

An objective of the invention is providing a multi-band antenna array (e.g., 100, 300a, 300b, 500a, 500b, 500c, 600a, 600b, 700, 800, 900a or 900b in FIG. 1, 3a, 3b, 5a, 5b, 5c, 6a, 6b, 7, 8, 9a or 9b) of improved compactness. The antenna array may include a plurality of first antennas (e.g., a1 to a4 in FIGS. 1, 2, 3a, 3b, 4a, 4b, 5a, 5b, 5c, 6a, 6b, 7 or 9b; a1 to a4 and a1c in FIGS. 9a; or, a1 to a9 in FIG. 8) for resonating at a first band (e.g., low-band), and a plurality of second antennas (e.g., b1 to b4 in FIG. 1, 2, 3a, 3b, 4a, 4b, 5a, 5b, 5c, 6a, 6b, 7 or 9a; or, b1 to b4 and b1c in FIG. 9b; or, b1 to b12 in FIG. 8) for resonating at a second band (e.g., low-band). A frequency of the second band may be higher than a frequency of the first band. Locations of the plurality of first antennas may respectively project to a plurality of grid-one positions (e.g., p1 to p4 in FIGS. 1, 2, 3a, 3b, 3c, 4a, 4b, 5a, 5b, 5c, 6a, 6b, 7 or 9b; or, p1 to p4 and p1c in FIGS. 9a; or, p1 to p9 in FIG. 8) on a surface (e.g., xy1 in FIG. 1, 2, 3a, 3b, 4a, 4b, 5a, 5b, 5c, 6a, 6b, 7, 8, 9a or 9b). Locations of the plurality of second antennas may respectively project to a plurality of grid-two positions (e.g., u1 to u4 in FIG. 1, 2, 3a, 3b, 3c, 4a, 4b, 5a, 5b, 5c, 6a, 6b, 7 or 9a; or, u1 to u12 in FIG. 8; or, u1 to u4 and u1c in FIG. 9b) on the surface (e.g., xy1). Among the plurality of grid-one positions, a second grid-one position (e.g., p2 in FIG. 1, 2, 3a, 3b, 3c, 4a, 4b, 5a, 5b, 5c, 6a, 6b, 7, 8 or 9b; or, p1c in FIG. 9a) of the plurality of grid-one position may be nearest to a first grid-one position (e.g., p1 in FIG. 1, 2, 3a, 3b, 3c, 4a, 4b, 5a, 5b, 5c, 6a, 6b, 7, 8, 9a or 9b) of the plurality of grid-one position by a first distance (e.g., d1 in FIG. 1, 3a, 3b, 7, 8 or 9b; or, d1c in FIG. 9a) along a first direction (e.g., v1 in FIG. 1, 3a, 3b, 5a, 7, 8 or 9a; or, v1c in FIG. 9a). Among the plurality of grid-two positions, a first grid-two position and a second grid-two position (e.g., u1 and u2 in FIG. 1, 2, 3a, 3b, 3c, 4a, 4b, 5a, 5b, 5c, 6a, 6b, 7, 8, 9a or 9b) of the plurality of grid-two positions are closest two to the first grid-one position. The first grid-two position and the second grid-two position may be separated by a second distance (e.g., d2 in FIG. 1, 3a, 3b, 7, 8, 9a or 9b) along a second direction (e.g., v2 in FIG. 1, 3a, 3b, 5a, 7, 8, 9a or 9b). According to the invention, the first direction and the second direction may be nonparallel.

In an embodiment (e.g., FIG. 1, 3a, 3b, 7, 8, 9a or 9b), the second distance (e.g., d2) may not be longer than the first distance (e.g., d1 or d1c). In an embodiment, (e.g., FIG. 1, 3a, 3b, 7, 8 or 9b), the second distance may be shorter than the first distance.

In an embodiment (e.g., FIG. 1), the second grid-two position (e.g., u2) may be on a first geometric line segment between the first grid-one position (e.g., p1) and the second grid-one position (e.g., p2). In an embodiment (e.g., FIG. 1), the second grid-two position may be at a midpoint of the first geometric line segment.

In an embodiment (e.g., FIG. 1), a ratio (e.g., d1/d2) dividing the first distance (e.g., d1) by the second distance (e.g., d2) may positively correlate to a ratio (e.g., f2/f1) dividing the frequency (e.g., f2) of the second band by the frequency (e.g., f1) of the first band. In an embodiment (e.g., FIG. 1), a ratio (e.g., d1/d2) dividing the first distance (e.g., d1) by the second distance (e.g., d2) may be substantially equal to a ratio (e.g., f2/f1) dividing the frequency (e.g., f2) of the second band by the frequency (e.g., f1) of the first band.

In an embodiment (e.g., FIG. 1), an angle between the first direction (e.g., v1) and the second direction (e.g., v2) may substantially equal 45 degrees.

In an embodiment (e.g., FIG. 1, 3a, 3b, 7, 8, 9a or 9b), among the plurality of grid-one positions, a third grid-one position (e.g., p4) of the plurality of grid-one positions may be second nearest to the first grid-one position (e.g., p1) by a third distance (e.g., d3) along a third direction (e.g., v3), and the third direction may be nonparallel to the first direction (e.g., v1 or v1c) and the second direction (e.g., v2).

In an embodiment (e.g., FIG. 1), the second grid-two position (e.g., u2) may be on a first geometric line segment between the first grid-one position (e.g., p1) and the second grid-one position (e.g., p2), and the first grid-two position (e.g., u1) is on a second geometric line segment between the first grid-one position (e.g., p1) and the third grid-one position (e.g., p3). In an embodiment (e.g., FIG. 1), the first grid-two position (e.g., u1) may be at a midpoint of the second geometric line segment.

In an embodiment (e.g., FIG. 1, 3a, 3b, 7, 8, 9a or 9b), the second direction (e.g., v2) may not be perpendicular to the first direction (e.g., v1 or v1c) and the third direction (e.g., v3).

In an embodiment (e.g., FIG. 1), the third direction (e.g., v3) may be substantially perpendicular to the first direction (e.g., v1). In an embodiment (e.g., FIG. 1), the third distance (e.g., d3) may be substantially equal to the first distance (e.g., d1).

In an embodiment (e.g., FIG. 4a or 4b), each of a subset (none, one, some or all) of the plurality of first antennas may include two first feed terminals, for two orthogonal polarization operation. In an embodiment, (e.g., FIG. 4a or 4b), each of a subset (none, one some or all) of the plurality of second antennas may include two second feed terminals, for two orthogonal polarization operation.

In an embodiment (e.g., FIG. 6a or 6b), the antenna array (e.g., 600a or 600b) may further include one or more parasitic elements (e.g., pa1 to pa8 or pb1 to pb8 in FIG. 6a or 6b).

In an embodiment (e.g., FIG. 7), the antenna array (e.g., 700) may further include a plurality of third antennas (e.g., c1 to c4), for resonating at a third band (e.g., higher high-band). A frequency of the third band may be higher than the frequency of the second band (e.g., high-band). Locations the plurality of third antennas may respectively project to a plurality of grid-three positions (e.g., k1 to k4)

on the surface (e.g., $xy1$). Among the plurality of grid-three positions (e.g., $k1$ to $k4$), a first grid-three position and a second grid-three position (e.g., $k1$ and $k2$) of the plurality of grid-three positions may be closest two to the second grid-two position (e.g., $u2$); and, the first grid-three position and the second grid-three position (e.g., $k1$ and $k2$) may be mutually separated by a fourth distance (e.g., $d4$) along a fourth direction (e.g., $v4$). The fourth direction (e.g., $v4$) and the second direction (e.g., $v2$) may be nonparallel.

In an embodiment (e.g., FIG. 7), the fourth distance (e.g., $d4$) may not be longer than the second distance (e.g., $d2$). In an embodiment (e.g., FIG. 7), the first grid-three position (e.g., $k1$) is on a geometric line segment between the first grid-two position (e.g., $u1$) and the second grid-two position (e.g., $u2$).

In an embodiment (e.g., FIG. 9b), among the plurality of grid-one positions, a third grid-one position (e.g., $p4$) and a fourth grid-one position (e.g., $p3$) of the plurality of grid-one positions may be second and third nearest to the first grid-one position (e.g., $p1$); and, a third grid-two position (e.g., $u1c$) of the plurality of grid-two positions is inside a geometric polygon (e.g., $p1-p2-p3-p4$) formed by vertices at the first grid-one position, the second grid-one position, the third grid-one position and the fourth grid-one position.

Numerous objects, features and advantages of the present invention will be readily apparent upon a reading of the following detailed description of embodiments of the present invention when taken in conjunction with the accompanying drawings. However, the drawings employed herein are for the purpose of descriptions and should not be regarded as limiting.

BRIEF DESCRIPTION OF THE DRAWINGS

The above objects and advantages of the present invention will become more readily apparent to those ordinarily skilled in the art after reviewing the following detailed description and accompanying drawings, in which:

FIG. 1 illustrates a top view of an antenna array according to an embodiment of the invention;

FIG. 2 illustrates a three-dimension view and a side view of the antenna array in FIG. 1 according to an embodiment of the invention;

FIG. 3a illustrates a top view of an antenna array according to an embodiment of the invention;

FIG. 3b illustrates a top view of an antenna array according to an embodiment of the invention;

FIG. 3c illustrates a top view of possible antenna placement range according to an embodiment of the invention;

FIG. 4a illustrates a top view of feed terminal placement of the antenna array in FIG. 1 according to an embodiment of the invention;

FIG. 4b illustrates a top view of feed terminal placement of the antenna array in FIG. 1 according to an embodiment of the invention;

FIG. 5a illustrates a top view of an antenna array according to an embodiment of the invention;

FIG. 5b illustrates a top view of an antenna array according to an embodiment of the invention;

FIG. 5c illustrates a top view of an antenna array according to an embodiment of the invention;

FIG. 6a illustrates a top view of an antenna array according to an embodiment of the invention;

FIG. 6b illustrates a top view of an antenna array according to an embodiment of the invention;

FIG. 7 illustrates a top view of an antenna array according to an embodiment of the invention;

FIG. 8 illustrates a top view of an antenna array according to an embodiment of the invention;

FIG. 9a illustrates a top view of an antenna array according to an embodiment of the invention; and

FIG. 9b illustrates a top view of an antenna array according to an embodiment of the invention.

DETAILED DESCRIPTION OF PREFERRED EMBODIMENTS

Please refer to FIG. 1 illustrating a top view of an antenna array 100 according to an embodiment of the invention; the antenna array 100 may be a multi-band antenna array (antenna module). The antenna array 100 may include a plurality of low-band antennas, such as $a1$, $a2$, $a3$ and $a4$, for electromagnetic resonating at a low-band of a frequency $f1$. The antenna array 100 may also include a plurality of high-band antennas, such as $b1$, $b2$, $b3$ and $b4$, for electromagnetic resonating at a high-band of a frequency $f2$. The frequency $f2$ of the high-band may be higher than the frequency $f1$ of the low-band. The low-band antennas $a1$ to $a4$ may form a low-band subarray, and the high-band antennas $b1$ to $b4$ may form a high-band subarray.

The low-band antennas $a1$ to $a4$ and the high-band antennas $b1$ to $b4$ may be disposed near the same surface or near different surfaces; for example, as shown in FIG. 2, the antennas $a1$ to $a4$ may be disposed near a surface $xy1$ (e.g., an x-y plane), the antenna $b1$ to $b4$ may be disposed near a surface $xy2$, wherein the surfaces $xy1$ and $xy2$ may be the same surface, or be different surfaces. Locations of the low-band antennas $a1$ to $a4$ may project to positions $p1$ to $p4$ on the surface $xy1$. Locations of the high-band antennas $b1$ to $b4$ may project to positions $u1$ to $u4$ on the surface $xy1$. Each of the low-band antennas $a1$ to $a4$ may be a patch antenna, a PIFA (planar inverted-F antenna), a loop antenna, or a slot antenna, etc. Similarly, each of the high-band antennas $b1$ to $b4$ may be a patch antenna, a PIFA, a loop antenna, or a slot antenna, etc. Optionally, as shown in FIG. 2, the antenna array 100 may further include one or more antenna director layers, e.g., $Ld0$, parallel to the surfaces $xy1$ and $xy2$. The antenna director layer(s) may be insulated to the antennas $a1$ to $a4$ and $b1$ to $b4$, e.g., be separated from the antennas $a1$ to $a4$ and $b1$ to $b4$ by dielectric materials and/or air-filled space. The antenna director layer(s) $Ld0$ may be formed by metal(s) or material(s) of high dielectric constant(s), and may therefore enhance directional gain of the antenna array 100.

In general, a position of an antenna may refer to a geometric point, or a projection (to the surface $xy1$) of a geometric point, which has a predefined geometric relation with other geometric points of the antenna, and/or has a predefined geometric relation with geometric characteristics of the antenna. For example, a position of an antenna may refer to a geometric center (or a projection of the geometric center) of the antenna, or a midpoint (or a projection of the midpoint) on a given edge of the antenna, or a partition point (or a projection of the partition point) which divides a line segment between two given geometric points (e.g., vertices) of the antenna by a predefined ratio, etc.; or, a position of an antenna may refer to a location (or a projection of the location) of a feed terminal or a ground terminal of the antenna.

No matter whether the low-band antennas $a1$ to $a4$ and the high-band antennas $b1$ to $b4$ are on the same surface or on different surfaces (as shown in FIG. 2), in an embodiment, projected planar placement of the antennas $a1$ to $a4$ and $b1$ to $b4$ may be arranged according to FIG. 1. As shown in FIG.

1, among the positions p1 to p4 of the low-band antennas a1 to a4, the position p2 of the antenna a2 may be nearest to the position p1 of the antenna a1 by a distance d1 along a direction v1. That is, the distance d1 between the positions p1 and p2 may be shorter than or equal to a distance between the positions p1 and p3, and be shorter than or equal to a distance between the positions p1 and p4. The positions p1 to p4 of the low-band antennas a1 to a4 may be considered as grid-one positions indicative of a grid of the low-band subarray, and the direction v1 may indicate a direction of the grid of the low-band subarray; on the other hand, the positions u1 to u4 of the high-band antennas b1 to b4 may be considered as grid-two positions indicative of a grid of the high-band subarray.

Among the positions u1 to u4 of the high-band antennas b1 to b4, the positions u1 and u2 may be the closest two to the position p1 of the low-band antenna a1; i.e., for the position p1, one of the positions u1 and u2 may be the most proximate one of the positions u1 to u4, and the other one of the positions u1 and u2 may be the second most proximate one of the positions u1 to u4. That is, a distance ds1 between the positions p1 and u1 or a distance ds2 between the positions p1 and u2 may be shorter than or equal to a distance between the positions p1 and u3, and be shorter than or equal to a distance between the positions p1 and u4.

The two positions u1 and u2 closest to the position p1 may be mutually separated by a distance d2 along a direction v2. The direction v2 may indicate a direction of the grid of the high-band subarray. According to the invention, the direction v1 pointing from the positions p1 to p2 and the direction v2 pointing from the positions u1 to u2 may be arranged to be nonparallel. For example, as shown in FIG. 1, an angle between the direction v1 and the direction v2 may substantially equal 45 degrees. By arranging the directions v1 and v2 to be nonparallel, the high-band subarray formed by the high-band antennas b1 to b4 may be integrated among the low-band subarray formed by the low-band antennas a1 to a4, so as to improve compactness of the multi-band antenna array 100.

In an embodiment, the distance d2 between the positions u1 and u2 may be shorter than (or equal to) the distance d1 between the positions p1 and p2. For better radiation pattern of the high-band subarray, in an embodiment, the distance d2 may be set shorter than or equal to a half of a wavelength of the high-band. Similarly, for better radiation pattern of the low-band subarray, in an embodiment, the distance d1 may be set shorter than or equal to a half of a wavelength of the low-band. While a wavelength of a band is proportional to a reciprocal of a frequency of the band, the wavelength of the high-band is shorter than the wavelength of the low-band; thus, by setting the distance d2 shorter than (or equal to) the distance d1, both the low-band subarray and the high-band subarray may benefit from better radiation patterns.

In an embodiment, a distance ratio d1/d2 dividing the distance d1 by the distance d2 may positively correlate to a frequency ratio f2/f1 dividing the frequency f2 of the high-band by the frequency f1 of the low-band; that is, if the ratio f2/f1 is larger due to implementation demands, the ratio d1/d2 may be designed to be larger. In an embodiment, the distance ratio d1/d2 may be substantially equal to the frequency ratio f2/f1. For example, in an embodiment, the frequencies f1 and f2 may respectively be 28 GHz and 39 GHz, the ratio f2/f1 may therefore approximately be 1.4, and the distance d2 may be set substantially equal to d1/1.4, or approximately 0.7*d1.

Among the positions p1 to p4 of the low-band antennas a1 to a4, while the position p2 may be the nearest to the position p1, the position p4 may be second nearest to the position p1 by a distance d3 along a direction v3; i.e., the distance d3 between the position p1 and p4 may be longer than or equal to the distance d1 between the positions p1 and p2, but be shorter than or equal to the distance between the positions p1 and p3. In an embodiment, the direction v3 may be arranged to be nonparallel to the directions v1 and v2. For example, as shown in FIG. 1, in an embodiment, the direction v3 may be substantially perpendicular to the direction v1. In an embodiment, the distance d2 may be shorter than or equal to the distance d3.

In an embodiment, as shown in FIG. 1, the position u2 15 may be placed on a geometric line segment p1-p2 between the positions p1 and p2. For example, in an embodiment, the position u2 may be placed at a midpoint of the line segment p1-p2, such that the distance ds2 between the positions p1 and u2 may substantially equal to a half of the distance d1. 20 In a different embodiment, the position u2 may be placed on the line segment p1-p2, but at a point other than the midpoint of the line segment p1-p2, such that the distance ds2 may differ from a half of the distance d1. In yet another embodiment, the position u2 may not be placed on the line segment p1-p2.

In an embodiment, the position u1 may be placed on a geometric line segment p1-p4 between the positions p1 and p4. For example, in an embodiment, the position u1 may be placed at a midpoint of the line segment p1-p4, such that the 30 distance ds1 between the positions p1 and u1 may substantially equal to a half of the distance d3. In a different embodiment, the position u1 may be placed on the line segment p1-p4, but at a point different from the midpoint of the line segment p1-p4, such that the distance ds1 may differ from a half of the distance d3. In yet another embodiment, the position u1 may not be on the line segment p1-p4.

Regarding the position p3 of the low-band antenna a3, a direction from the positions p4 to p3 may be set parallel or nonparallel to the direction v1; and, a direction from the 40 positions p2 to p3 may be set parallel or nonparallel to the direction v3. A distance between the positions p3 and p4 may be set substantially equal to, or different from, the distance d1; and, a distance between the positions p2 and p3 may be set substantially equal to, or different from, the distance d3. In an embodiment, among the positions p1 to p4 of the low-band antennas a1 to a4, the positions p4 and p2 may be the nearest and the second nearest to the position p3.

Regarding the positions u3 and u4 of the high-band antennas b3 and b4, in an embodiment, a direction from the 50 positions u1 to u4 may be nonparallel to the directions v1, v2, and v3; for example, as shown in FIG. 1, the angle between the direction from the positions u1 to u4 and the direction v2 may be 90 degrees. The direction from the positions u1 to u4 may be parallel or nonparallel to a 55 direction from the positions u2 to u3; and, a direction from the positions u4 to u3 may be parallel or nonparallel to the direction v2. In an embodiment, the position u4 may be placed on a geometric line segment p3-p4 between the positions p3 and p4; in a different embodiment, the position u4 may not be placed on the geometric line segment p3-p4. In an embodiment, the position u3 may be placed on a geometric line segment p2-p3 between the positions p2 and p3; in a different embodiment, the position u3 may not be placed on the geometric line segment p2-p3.

As shown in FIG. 1, in an embodiment for multi-band of frequencies f1=28 GHz and f2=39 GHz, the directions v1 and v3 may be perpendicular, the direction from positions p4

to p_3 may be parallel to the direction v_1 , the direction from positions p_2 to p_3 may be parallel to the direction v_3 , the distances d_1 and d_3 may be set equal, and the positions u_1 , u_2 , u_3 and u_4 may respectively be placed at the midpoints of the line segments p_1-p_4 , p_1-p_2 , p_2-p_3 and p_3-p_4 , so the positions p_1 to p_4 may form four vertices of a geometric square $p_1-p_2-p_3-p_4$, and the positions u_1 to u_4 may form four vertices of a geometric square $u_1-u_2-u_3-u_4$ inside the square $p_1-p_2-p_3-p_4$. Under such arrangement, the distance d_2 may be equal to $\sqrt{(d_1^2 + d_3^2)/2} = d_1 * \sqrt{2}/2$ (with $\sqrt{}$ denoting a square root), or approximately $0.7 * d_1$, such that the distance ratio d_1/d_2 will approximately match the desired frequency ratio f_2/f_1 .

Though the positions u_1 to u_4 are shown to be on the edges of the geometric polygonal $p_1-p_2-p_3-p_4$ in FIG. 1, the invention is not so limited. Please refer to FIG. 3a illustrating a top view of a multi-band antenna array 300a. Similar to the antenna array 100 in FIG. 1, the antenna array 300a in FIG. 3a may include low-band antennas a_1 to a_4 and high-band antennas b_1 to b_4 ; location of the antennas a_1 to a_4 may project to positions p_1 to p_4 on the surface xy_1 , and locations of the antennas b_1 to b_4 may project to positions u_1 to u_4 on the surface xy_1 . Among the positions p_1 to p_4 , the positions p_2 and p_4 may be the nearest and the second nearest to the position p_1 , wherein the position p_1 may be adjacent to the position p_2 along a direction v_1 by a distance d_1 , and be adjacent to the position p_4 along a direction v_3 by a distance d_3 . Among the positions u_1 to u_4 , the positions u_1 and u_2 may be the closest two to the position p_1 , and the positions u_1 and u_2 may be separated by a distance d_2 along a direction v_2 . The directions v_2 may be nonparallel to the directions v_1 and v_3 . As shown in FIG. 3a, in an embodiment, a subset (one, some or all) of the positions u_1 to u_4 may not be on any edge of the geometric polygonal $p_1-p_2-p_3-p_4$. For example, a first subset (none, one, some or all) of the positions u_1 to u_4 may be placed inside the polygonal $p_1-p_2-p_3-p_4$; and/or, a different second subset (none, one, some or all) of the positions u_1 to u_4 may be placed outside the polygonal $p_1-p_2-p_3-p_4$.

Though the directions v_1 and v_3 are shown to be perpendicular in FIG. 1, the invention is not so limited. Please refer to FIG. 3b illustrating a top view of a multi-band antenna array 300b. Similar to the antenna array 100 and 300a in FIG. 1 and FIG. 3a, the antenna array 300b in FIG. 3b may include low-band antennas a_1 to a_4 and high-band antennas b_1 to b_4 ; locations of the antennas a_1 to a_4 may project to position p_1 to p_4 on the surface xy_1 , and locations of the antennas b_1 to b_4 may project to positions u_1 to u_4 on the surface xy_1 . Among the positions p_1 to p_4 , the positions p_2 and p_4 may be the nearest and the second nearest to the position p_1 , wherein the position p_1 may be adjacent to the position p_2 along a direction v_1 by a distance d_1 , and be adjacent to the position p_4 along a direction v_3 by a distance d_3 . Among the positions u_1 to u_4 , the positions u_1 and u_2 may be the closest two to the position p_1 , and the positions u_1 and u_2 may be separated by a distance d_2 along a direction v_2 . The directions v_2 may be set nonparallel to the directions v_1 and v_3 . As shown in FIG. 3b, in an embodiment, the directions v_1 and v_3 may not be perpendicular; i.e., an angle between the directions v_1 and v_3 may be less than or greater than 90 degrees.

Though in FIG. 1 the direction from the positions p_4 to p_3 is shown to be parallel to the direction v_1 , and the direction from positions p_2 to p_3 is shown to be parallel to the direction v_3 , the invention is not so limited. As shown in FIG. 3b, the direction from the positions p_4 to p_3 may be

nonparallel to the direction v_1 ; and/or, the direction from positions p_2 to p_3 may be nonparallel to the direction v_3 .

Along with FIG. 1 and FIGS. 3a to 3b, please refer to FIG. 3c illustrating a top view of possible placement range of the low-band antenna positions p_1 to p_4 and the high-band antenna positions u_1 to u_4 . The positions u_1 to u_4 of the high-band antennas b_1 to b_4 may locate in a range bounded between an inner geometric polygonal $u_1-u_2-u_3-u_4$ and an outer geometric polygonal $u_1-u_2-u_3-u_4$. Without causing the antennas a_1 to a_4 to overlap projection of any one of the antennas b_1 to b_4 , the positions p_1 to p_4 of the low-band antennas a_1 to a_4 may locate in a range bounded between an inner geometric polygonal $p_1-p_2-p_3-p_4$ and an outer geometric polygonal $p_1-p_2-p_3-p_4$. Each edge of the polygonal $u_1-u_2-u_3-u_4$ may be nonparallel to either edge of the polygonal $p_1-p_2-p_3-p_4$, and/or be nonparallel to either edge of the polygonal $p_1-p_2-p_3-p_4$. Each edge of the polygonal $u_1-u_2-u_3-u_4$ may be nonparallel to either edge of the polygonal $p_1-p_2-p_3-p_4$, and/or be nonparallel to either edge of the polygonal $p_1-p_2-p_3-p_4$. A geometric center of the polygonal $p_1-p_2-p_3-p_4$ may be inside the polygonal $u_1-u_2-u_3-u_4$; and/or, a geometric center of the polygonal $p_1-p_2-p_3-p_4$ may be inside the polygonal $u_1-u_2-u_3-u_4$.

In the antenna array 100 (FIG. 1), each of the low-band antennas a_1 to a_4 may include one or more feed terminals for relaying one or more low-band feed signals; for example, each of a subset (none, one, some or all) of the antennas a_1 to a_4 may include two feed terminals for two orthogonal polarization operation. Similarly, each of the high-band antennas b_1 to b_4 may include one or more second feed terminals for relaying one or more high-band feed signals; for example, each of a subset (none, one, some or all) of the antennas b_1 to b_4 may include two feed terminals for two orthogonal polarization operation. Along with FIG. 1, please refer to FIG. 4a; FIG. 4a illustrates a top view of feed terminal placement according to an embodiment of the invention. As shown in FIG. 4a, in the antenna array 100, the antenna a_1 may include two feed terminals na_1 and na_2 , the antenna a_2 may include two feed terminals na_3 and na_4 , the antenna a_3 may include two feed terminals nay and na_6 , and the antenna a_4 may include two feed terminals na_1 and na_8 . Furthermore, the antenna b_1 may include two feed terminals nb_1 and nb_2 , the antenna b_2 may include two feed terminals nb_3 and nb_4 , the antenna b_3 may include two feed terminals nb_5 and nb_6 , and the antenna b_4 may include two feed terminals nb_7 and nb_8 .

As shown in FIG. 4a, in an embodiment, the feed terminals nb_1 to nb_8 of the high-band antennas b_1 to b_4 may be arranged outward from a geometric reference point c_0 ; that is, within each high-band antenna, its two feed terminals may be placed at locations farther from the reference point c_0 . In another embodiment not shown, the feed terminals nb_1 to nb_8 of the high-band antennas b_1 to b_4 may be arranged toward the reference point c_0 . The reference point c_0 may be a geometric point inside the polygonal $p_1-p_2-p_3-p_4$, and/or inside the polygonal $u_1-u_2-u_3-u_4$; for example, the reference point c_0 may be a geometric center of the polygonal $p_1-p_2-p_3-p_4$ or the polygonal $u_1-u_2-u_3-u_4$. The feed terminals na_1 to na_8 of the low-band antennas a_1 to a_4 may also be arranged outward from the reference point c_0 .

Along with FIG. 1 and FIG. 4a, please refer to FIG. 4b; FIG. 4b illustrates a top view of feed terminal placement according to yet another embodiment of the invention. As shown in FIG. 4b, in an embodiment, some of the feed terminals nb_1 to nb_8 may be arranged toward the reference

point **c0**, while others may be arranged outward from the reference point **c0**. For example, as shown in FIG. 4*b*, within the antenna **b1**, the feed terminals **nb1** of the antenna **b1** may be placed at a location closer to the reference point **c0**, while the other feed terminals **nb2** of the antenna **b1** may be placed at a location farther from the reference point **c0**. Though not shown in FIGS. 4*a* and 4*b*, it is understood that there may also be various embodiments for placing the feed terminals **na1** to **na8** of the low-band antennas **a1** to **a4**, similar to placement of the feed terminals **nb1** to **nb8**. Similar to FIGS. 4*a* and 4*b*, each of the antennas **a1** to **a4** and **b1** to **b4** in the antenna array **300a** or **300b** (FIG. 3*a* or 3*b*) may include one or more feed terminals, and there may be multiple different embodiments to arrange locations of the feed terminals.

Though shapes of the antennas **a1** to **a4** and **b1** to **b4** are shown to be rectangular in FIG. 1, the invention is not so limited. Along with FIG. 1, please refer to FIG. 5*a* illustrating a top view of an antenna array **500a** according to an embodiment of the invention; the antenna array **500a** in FIG. 5*a* may be achieved from the antenna array **100** in FIG. 1 by changing shapes of the antennas **a1** to **a4** and **b1** to **b4**. As shown in FIG. 5*a*, the geometric shapes of the antennas **b1** to **b4** may respectively orient along reference directions **vb1** to **vb4**; for example, the reference direction **vb1** of the antenna **b1** may be a geometric symmetry axis of its shape. In an embodiment, the reference direction **vb1** to **vb4** may point outward from (or toward) a geometric reference point **c0**. In an embodiment (not shown), the reference direction **vb1** to **vb4** may be parallel. In an embodiment (not shown), the reference directions **vb1** and **vb3** may be opposite, the reference directions **vb2** and **vb4** may be opposite, the reference direction **vb1** may be parallel or nonparallel to a horizontal *x*-axis, and the reference direction **vb2** may be parallel or nonparallel to a vertical *y*-axis. Though not shown in FIG. 5*a*, each of the low-band antenna **a1** to **a4** may also orient along its own reference direction, and there may be various embodiments to align the reference directions of the low-band antennas **a1** to **a4**, similar to the high-band antennas **b1** to **b4**.

Along with FIG. 1, please refer to FIG. 5*b* illustrating a top view of an antenna array **500b** according to an embodiment of the invention; the antenna array **500b** in FIG. 5*b* may be achieved from the antenna array **100** in FIG. 1 by changing orientations of the high-band antennas **b1** to **b4**. Along with FIG. 1, please refer to FIG. 5*c* illustrating an antenna array **500c** according to an embodiment of the invention; the antenna array **500c** in FIG. 5*c* may be achieved from the antenna array **100** in FIG. 1 by changing orientations of the low-band antennas **a1** to **a4**.

Along with FIG. 1, please refer to FIG. 6*a* illustrating a top view of an antenna array **600a** according to an embodiment of the invention; the antenna array **600a** in FIG. 6*a* may be developed from the antenna array **100** in FIG. 1 by further including one or more parasitic elements, such as **pa1** to **pa8**. The parasitic elements **pa1** to **pa8** and the antennas **a1** to **a4** may be disposed near the same surface **xy1**. The parasitic elements **pa1** to **pa8** may be formed by conductor (metal), and be insulated from the antennas **a1** to **a4** and **b1** to **b4**. As shown in FIG. 6*a*, in an embodiment, the parasitic elements **pa1** to **pa8** may be placed near outer edges (with respect to a reference point **c0**) of the antennas **a1** to **a4**. For example, the parasitic elements **pa1** and **pa8** may be placed near a top edge and a left edge of the antenna **a1**, since the top edge and the left edge are farther from the reference point **c0** comparing to the other two edges of the antenna **a1**.

Along with FIG. 1, please refer to FIG. 6*b* illustrating a top view of an antenna array **600b** according to an embodiment

of the invention; the antenna array **600b** in FIG. 6*b* may be developed from the antenna array **100** in FIG. 1 by further including one or more parasitic elements, such as **pb1** to **pb8**. The parasitic elements **pb1** to **pb8** and the antennas **b1** to **b4** may be disposed near the same surface (e.g., **xy1** or **xy2** in FIG. 2). The parasitic elements **pb1** to **pb8** may be formed by conductor (metal), and be insulated from the antennas **a1** to **a4** and **b1** to **b4**. As shown in FIG. 6*b*, in an embodiment, the parasitic elements **pb1**, **pb3**, **pb5** and **pb7** may be placed near outer edges (with respect to a reference point **c0**) of the antennas **b1** to **b4**, while the parasitic elements **pb2**, **pb4**, **pb6** and **pb8** may be placed near inner edges of the antennas **b1** to **b4**. For example, among all edges of the antenna **b1**, its left edge and right edge are the farthest and the closest to the reference point **c0**, and the parasitic elements **pb1** and **pb2** may be respectively placed near the left edge and the right edge of the antenna **b1**.

Along with FIG. 1, please refer to FIG. 7 illustrating a top view of an antenna array **700** according to an embodiment of the invention; the antenna array **700** in FIG. 7 may be developed from the antenna array **100** in FIG. 1 by further including one or more higher high-band antennas, e.g., **c1** to **c4**, for resonating at a higher high-band, wherein the a frequency **f3** of the higher high-band may be higher than the frequency **f2** of the high-band. The antennas **c1** to **c4** may be disposed near a surface (e.g., **xy1** in FIG. 2) which the antennas **a1** to **a4** are disposed near, near a surface (e.g., **xy2** in FIG. 2) which the antennas **b1** to **b4** are disposed near, or near a surface other than the surface(s) which the antennas **a1** to **a4** and **b1** to **b4** are disposed near. The antennas **c1** to **c4** may form a higher high-band subarray.

As shown in FIG. 7, locations the higher high-band antennas **c1** to **c4** may respectively project to positions **k1** to **k4** on the surface **xy1**, and the positions **k1** to **k4** may be considered as grid-three positions indicative of a grid of the higher high-band subarray. Among the positions **k1** to **k4** of the higher high-band antennas **c1** to **c4**, the positions **k1** and **k2** may be the closest two to the position **u2**, and the positions **k1** and **k2** may be mutually separated by a distance **d4** along a direction **v4**. According to an embodiment of the invention, the directions **v4** and **v2** may be nonparallel. For example, in an embodiment, an angle between the directions **v2** and **v4** may be set substantially equal to 45 degrees. In an embodiment, the distance **d4** may not be longer than the distance **d2**; for example, the distance **d4** may be shorter than the distance **d2**. In an embodiment, each of a subset (none, one, some or all) of the positions **k1** to **k4** may be on an edge of the geometric polygonal **b1-b2-b3-b4**; for example, in an embodiment, the position **k1** may be on the geometric line segment between the positions **u1** and **u2**. In an embodiment, a subset (none, one, some or all) of the positions **k1** to **k4** may not be on any edge of the geometric polygonal **b1-b2-b3-b4**.

As shown in FIG. 7, in an embodiment for multi-band frequencies **f1**=28 GHz, **f2**=39 GHz and **f3**=60 GHz, the directions **v1** and **v3** may be perpendicular; the direction from the positions **p4** to **p3** may be parallel to the direction **v1**, and the direction from the positions **p2** to **p3** may be parallel to the direction **v3**; a direction from the positions **u4** to **u3** may be parallel to the direction **v2**, a direction from the positions **u2** to **u3** may be parallel to a direction from the positions **u1** to **u4**, and the direction **v2** may be perpendicular to the direction from the positions **u1** to **u4**; a direction from the positions **k4** to **k3** may be parallel to the direction **v4**, a direction from the positions **k1** to **k4** may be parallel to a direction from the positions **k2** to **k3**, and the direction from the positions **k1** to **k4** may be perpendicular to the

direction v_4 ; the directions v_1 and v_4 may be parallel, and the direction from the positions k_1 to k_4 may be parallel to the direction v_3 ; furthermore, the distances d_1 and d_3 may be set equal, a distance between the positions u_1 and u_4 may be equal to the distance d_2 , and a distance between the positions k_1 and k_4 may be equal to the distance d_4 ; the positions u_1 , u_2 , u_3 and u_4 may respectively be placed at the midpoints of the line segments p_1-p_4 , p_1-p_2 , p_2-p_3 and p_3-p_4 , and the positions k_1 , k_2 , k_3 and k_4 may respectively be placed at midpoints of geometric line segments u_1-u_2 , u_2-u_3 , u_3-u_4 and u_4-u_1 , so the positions p_1 to p_4 may form four vertices of a geometric square $p_1-p_2-p_3-p_4$, the positions u_1 to u_4 may form four vertices of a geometric square $u_1-u_2-u_3-u_4$ inside the square $p_1-p_2-p_3-p_4$, and the positions k_1 to k_4 may form four vertices of a geometric square $k_1-k_2-k_3-k_4$ inside the geometric square $u_1-u_2-u_3-u_4$.

Similar to feed terminal arrangement of the low-band antennas a_1 to a_4 and the high-band antennas b_1 to b_4 , each of the higher high-band antennas c_1 to c_4 in FIG. 7 may include one or more feed terminals (not shown in FIG. 7) for relaying one or more higher high-band feed signals.

Similar to FIGS. 5a to 5c, each of the antennas a_1 to a_4 , b_1 to b_4 and c_1 to c_4 in the antenna array 700 may be of any shape oriented to any direction. Similar to FIG. 6a and/or FIG. 6b, the antenna array 700 may further include one or more parasitic elements (not shown) near the antennas a_1 to a_4 , b_1 to b_4 and/or c_1 to c_4 .

Along with FIG. 1, please refer to FIG. 8 illustrating a top view of an antenna array 800 according to an embodiment of the invention; the antenna array 100 in FIG. 1 may be expanded to the antenna array 800 by further including more low-band antennas such as a_5 to a_9 , and more high-band antennas such as b_5 to b_{12} . As the low-band antennas a_1 to a_4 may be disposed near the surface xy_1 , the additional low-band antennas a_5 to a_9 may also be disposed near the surface xy_1 , wherein locations of the additional low-band antennas a_5 to a_9 may respectively project to positions p_5 to p_9 at the surface xy_1 . As the high-band antennas b_1 to b_4 may be disposed near the surface xy_2 (FIG. 2), the additional high-band antennas b_5 to b_{12} may also be disposed near the surface xy_2 , wherein locations of the antennas b_5 to b_{12} may project to positions u_5 to u_{12} on the surface xy_1 . A placement pattern to place the antennas a_1 to a_4 and b_1 to b_4 may be spatially repeated to place the other antennas a_5 to a_9 and b_5 to b_{12} . For example, a geometric relation between the positions p_2 , p_5 , p_6 and p_3 of the antennas a_2 , a_5 , a_6 and a_3 may be the same as a geometric relation between the position p_1 to p_4 of the antennas a_1 to a_4 ; and, a geometric relation between the positions u_3 , u_5 , u_6 , u_7 and p_2 , p_5 , p_6 and p_3 of the antennas b_3 , b_5 , b_6 , b_7 and a_2 , a_5 , a_6 and a_3 may be the same as a geometric relation between the positions u_1 to u_4 and p_1 to p_4 of the antennas a_1 to a_4 and b_1 to b_4 .

For example, regarding the positions p_1 to p_9 of the low-band antennas a_1 to a_9 , while the positions p_2 may be separated from the position p_1 by the distance d_1 along the direction v_1 , the positions p_5 may be separated from the position p_2 also by the distance d_1 along the direction v_1 ; while the positions p_4 may be separated from the position p_1 by the distance d_3 along the direction v_3 , the positions p_9 may be separated from the position p_4 also by the distance d_3 along the direction v_3 . On the other hand, regarding the positions u_1 to u_{12} of the high-band antennas b_1 to b_{12} , a geometric triangle $p_2-p_3-u_5$ formed by the positions p_2 , u_3 and u_5 may be congruent to a geometric triangle $p_1-u_1-u_2$ formed by the positions p_1 , u_1 and u_2 , with a direction from the positions u_3 to u_5 parallel to the direction v_2 ; and, a

geometric triangle $u_6-p_6-u_7$ formed by the positions u_6 , p_6 and u_7 may be congruent to a geometric triangle $u_3-p_3-u_4$ formed by the positions u_3 , p_3 and u_4 , with a direction from the positions u_6 to u_7 parallel to a direction from positions u_3 to u_4 .

Similar to the antennas a_1 to a_4 , each of the antennas a_5 to a_9 may include one or more low-band feed terminals (not shown) for relaying one or more low-band feed signals; similar to the antennas b_1 to b_4 , each of the antennas b_5 to b_{12} may include one or more feed terminals (not shown) for relaying one or more high-band feed signals. As the two-band antenna array 100 in FIG. 1 may be augmented to the three-band antenna array 700 in FIG. 7 by including the higher high band antennas c_1 to c_4 , the two-band antenna array 800 in FIG. 8 may also be augmented to a three-band antenna array (not shown) by further including higher high band antennas.

Similar to FIGS. 5a to 5c, the antennas a_1 to a_9 and b_1 to b_{12} in the antenna array 800 may be of any shape oriented to any direction. Similar to FIG. 6a and/or FIG. 6b, the antenna array 800 may further include one or more parasitic elements (not shown); for example, the antenna array 800 may include: three parasitic elements near top edges of the antennas a_1 , a_2 and a_5 ; three parasitic elements near left edges of the antennas a_1 , a_4 and a_9 ; three parasitic elements near right edges of the antennas a_5 , a_6 and a_7 ; and/or, three parasitic elements near bottom edges of the antennas a_7 , a_8 and a_9 .

Along with FIG. 1, please refer to FIG. 9a illustrating an antenna array 900a according to an embodiment of the invention; the antenna array 100 in FIG. 1 may be expanded to the antenna array 900a by further including an additional low-band antenna a_{1c} for resonating at the low-band. The low-band antenna a_{1c} may be disposed near the surface xy_1 ; a location of the antenna a_{1c} may project to a position p_{1c} on the surface xy_1 , and the position p_{1c} may be inside the geometric polygonal $p_1-p_2-p_3-p_4$. For example, the position p_{1c} may be a geometric center of the geometric polygonal $p_1-p_2-p_3-p_4$ or $u_1-u_2-u_3-u_4$. Among the positions p_1 to p_4 and p_{1c} of the low-band antennas a_1 to a_4 and a_{1c} , the position p_{1c} may be nearest to the position p_1 by a distance d_{1c} along a direction v_{1c} . Among the positions u_1 to u_4 of the high-band antennas b_1 to b_4 , the positions u_1 and u_2 may be the closest two to the position p_1 , and the positions u_1 and u_2 may be separated by the distance d_2 along the direction v_2 . According to the invention, the directions v_{1c} and v_2 may be set nonparallel. In an embodiment, the distance d_2 may not be longer than the distance d_{1c} ; for example, in an embodiment, the distance d_2 may substantially equal to the distance d_{1c} .

Similar to FIGS. 4a and 4b, in the antenna array 900a, each of the low-band antennas a_1 to a_4 and a_{1c} may include one or more feed terminals; and, each of the high-band antennas b_1 to b_4 may include one or more feed terminals. Similar to FIGS. 5a to 5c, each of the antennas a_1 to a_4 , a_{1c} and b_1 to b_4 in the antenna array 900a may be of any shape oriented to any direction. Similar to FIG. 6a and/or FIG. 6b, the antenna array 900a may further include one or more parasitic elements (not shown) near one or some of the antennas a_1 to a_4 , a_{1c} and b_1 to b_4 .

Along with FIG. 1, please refer to FIG. 9b illustrating an antenna array 900b according to an embodiment of the invention; the antenna array 100 in FIG. 1 may be expanded to the antenna array 900b by further including an additional high-band antenna b_{1c} for resonating at the high-band. As the high-band antennas b_1 to b_4 may be disposed near the surface xy_2 (FIG. 2), the high-band antenna b_{1c} may also be

13

disposed near the surface $xy2$, and location of the antenna $b1c$ may project to a position $u1c$ on the surface $xy1$. The position $u1c$ may be inside the geometric polygonal $u1-u2-u3-u4$. For example, the position $u1c$ may be a geometric center of the geometric polygonal $p1-p2-p3-p4$ or $u1-u2-u3-u4$. Among the positions $p1$ to $p4$ of the low-band antennas $a1$ to $a4$, the position $p2$ of the antenna $a2$ may be nearest to the position $p1$ of the antenna $a1$ by the distance $d1$ along the direction $v1$. Among the positions $u1$ to $u4$ and $u1c$ of the high-band antennas $b1$ to $b4$ and $b1c$, the positions $u1$ and $u2$ may still be closest two to the position $p1$, and the positions $u1$ and $u2$ may be separated by the distance $d2$ along the direction $v2$. According to the invention, the directions $v1$ and $v2$ may be set nonparallel.

Similar to FIGS. 4a and 4b, in the antenna array 900b, each of the low-band antennas $a1$ to $a4$ may include one or more feed terminals; and, each of the high-band antennas $b1$ to $b4$ and $b1c$ may include one or more feed terminals. Similar to FIGS. 5a to 5c, each of the antennas $a1$ to $a4$, $b1$ to $b4$ and $b1c$ in the antenna array 900b may be of any shape oriented to any direction. Similar to FIG. 6a and/or FIG. 6b, the antenna array 900b may further include one or more parasitic elements (not shown) near one or some of the antennas $a1$ to $a4$, $b1$ to $b4$ and $b1c$.

Similar to FIG. 7, the two-band antenna array 900a or 900b in FIG. 9a or 9b may be augmented to a three-band antenna array by further including higher high-band antennas. Similar to FIG. 8, the antenna array 900a or 900b in FIG. 9a or 9b may be expanded by further including more low-band antennas and high-band antennas which may be placed by repeating geometric placement pattern of the antenna array 900a or 900b.

Regarding the antenna array 300a or 300b in FIG. 3a or 3b, similar to FIGS. 5a to 5c, each of the antennas $a1$ to $a4$ and $b1$ to $b4$ in the antenna array 300a or 300b (FIG. 3a or 3b) may be of any shape oriented to any direction. Similar to FIG. 6a and/or FIG. 6b, the antenna array 300a or 300b in FIG. 3a or 3b may further include parasitic elements near the antennas $a1$ to $a4$ and/or $b1$ to $b4$. Similar to FIG. 7, the two-band antenna array 300a or 300b in FIG. 3a or 3b may be augmented to a three-band antenna array by further include one or more higher high-band antennas. Similar to FIG. 8, the antenna array 300a or 300b in FIG. 3a or 3b may be expanded by including more low-band antennas and/or high-band antennas. Similar to FIG. 9a or 9b, the antenna array 300a or 300b in FIG. 3a or 3b may be expanded by including an additional low-band antenna or high-band antenna at a position inside the geometric polygon $u1-u2-u3-u4$ and/or the geometric polygon $p1-p2-p3-p4$.

To sum up, by aligning grids of subarrays of different bands along different directions according to the invention, the subarrays of different bands may be nested into a constrained area, so as to improve compactness of multi-band antenna array.

While the invention has been described in terms of what is presently considered to be the most practical and preferred embodiments, it is to be understood that the invention needs not be limited to the disclosed embodiment. On the contrary, it is intended to cover various modifications and similar arrangements included within the spirit and scope of the appended claims which are to be accorded with the broadest interpretation so as to encompass all such modifications and similar structures.

What is claimed is:

1. A multi-band antenna array, comprising:
a plurality of first antennas for resonating at a first band;
and

14

a plurality of second antennas for resonating at a second band; wherein:

a frequency of the second band is higher than a frequency of the first band;

locations of the plurality of first antennas respectively

project to a plurality of grid-one positions on a surface;

locations of the plurality of second antennas respectively

project to a plurality of grid-two positions on the surface;

among the plurality of grid-one positions, a second grid-one position of the plurality of grid-one position is nearest to a first grid-one position of the plurality of grid-one position by a first distance along a first direction;

among the plurality of grid-two positions, a first grid-two position and a second grid-two position of the plurality of grid-two positions are closest two to the first grid-one position;

the first grid-two position and the second grid-two position are separated by a second distance along a second direction; and

the first direction and the second direction are nonparallel.

2. The multi-band antenna array of claim 1, wherein the second distance is not longer than the first distance.

3. The multi-band antenna array of claim 1, wherein the second distance is shorter than the first distance.

4. The multi-band antenna array of claim 1, wherein:
the second grid-two position is on a first geometric line segment between the first grid-one position and the second grid-one position.

5. The multi-band antenna array of claim 4, wherein:
the second grid-two position is at a midpoint of the first geometric line segment.

6. The multi-band antenna array of claim 1, wherein a ratio dividing the first distance by the second distance positively correlates to a ratio dividing the frequency of the second band by the frequency of the first band.

7. The multi-band antenna array of claim 1, wherein a ratio dividing the first distance by the second distance is substantially equal to a ratio dividing the frequency of the second band by the frequency of the first band.

8. The multi-band antenna array of claim 1, wherein an angle between the first direction and the second direction substantially equals 45 degrees.

9. The multi-band antenna array of claim 1, wherein:
among the plurality of grid-one positions, a third grid-one position of the plurality of grid-one positions is second nearest to the first grid-one position by a third distance along a third direction; and

the third direction is nonparallel to the first direction and the second direction.

10. The multi-band antenna array of claim 9, wherein:
the second grid-two position is on a first geometric line segment between the first grid-one position and the second grid-one position; and

the first grid-two position is on a second geometric line segment between the first grid-one position and the third grid-one position.

11. The multi-band antenna array of claim 10, wherein:
the first grid-two position is at a midpoint of the second geometric line segment.

12. The multi-band antenna array of claim 9, wherein:
the third direction is substantially perpendicular to the first direction.

13. The multi-band antenna array of claim 9, wherein:
the third distance is substantially equal to the first distance.

15

14. The multi-band antenna array of claim **1**, wherein: each of a subset of the plurality of first antennas comprises two first feed terminals, for two orthogonal polarization operation.

15. The multi-band antenna array of claim **1**, wherein: each of a subset of the plurality of second antennas comprises two second feed terminals, for two orthogonal polarization operation.

16. The multi-band antenna array of claim **1** further comprises one or more parasitic elements.

17. The multi-band antenna array of claim **1** further comprises:
a plurality of third antennas, for resonating at a third band; wherein:
a frequency of the third band is higher than the frequency of the second band;
locations the plurality of third antennas respectively project to a plurality of grid-three positions on the surface; among the plurality of grid-three positions, a first grid-three position and a second grid-three position of the plurality of grid-three positions are closest two to the second grid-two position;

5 the first grid-three position and the second grid-three position are mutually separated by a fourth distance along a fourth direction; and

the fourth direction and the second direction are nonparallel.

18. The multi-band antenna array of claim **17**, wherein the fourth distance is not longer than the second distance.

19. The multi-band antenna array of claim **18**, wherein the first grid-three position is on a geometric line segment 10 between the first grid-two position and the second grid-two position.

20. The multi-band antenna array of claim **1**, wherein: among the plurality of grid-one positions, a third grid-one position and a fourth grid-one position of the plurality of grid-one positions are second and third nearest to the first grid-one position; and a third grid-two position of the plurality of grid-two positions is inside a geometric polygon formed by vertices at the first grid-one position, the second grid-one position, the third grid-one position and the fourth grid-one position.
